CARBURETOR

Marion Mallory, Detroit, Mich.

Application April 28, 1938, Serial No. 204,865

6 Claims. (Cl. 261—52)

This invention relates to an improved carburetor having a throttle valve, a fuel metering pin connected thereto, an air valve and a venturi having a fuel nozzle associated therewith, located 5 between the air valve and throttle valve, and a velocity controlled air valve in the venturi adjacent the fuel nozzle.

One important object of the invention is to provide means to control the throttle and metering pin manually to increase or decrease the 10 volume of air and fuel and to open the air valve by suction and gravity only, but to control the rate of opening of the air valve in relation to the rate of opening of the throttle valve so as to 15 increase or decrease progressively and in synchronism the air volume, fuel volume and suction in the venturi.

A further object of the invention is to provide 20 means whereby the throttle and the air valve operate in synchronism part of the time as though they were positively connected together and further to provide means to cause the air valve to lag behind the throttle valve so as to automatically enrich the mixture for acceleration 25 and to prevent stalling of the engine on which the carburetor is used.

A further object of the invention is to provide 30 means to force most of the air past the fuel nozzle, in this type of carburetor, so as to straighten up the fuel flow and maintain sufficient suction around the nozzle at times when the volume of air passing through the carburetor is low.

A further object of the invention is to control 35 the air stream across the fuel jets, in this type of carburetor, to prevent air bleeding of any of the jets at times when the air valve is only partly open and also to control the rate and direction of opening of the air valve so as to produce a progressive suction curve at the nozzle without reduction, even though the suction around the nozzle does change from a static suction to a dynamic suction as the throttles are opened.

A further object of the invention is to provide 45 means to offer resistance to the opening of the air valve for starting and warm-up; this resistance decreasing rapidly as the air valve moves toward an open position and offering no resistance whatever when the air valve is wide open.

A further object of the invention is to provide 50 a metering pin in the form of a slide valve, so that the vacuum within the carburetor mixing chamber tends to hold the pin against the wall of the cylinder in which it operates, to prevent leakage and erratic metering.

A further object of the invention is to provide 5 means between the throttle valve and air valve, whereby resistance is offered to the opening of the air valve when the throttle valve is closed; said resistance increasing as the throttle valve is moved away from idle position, then rapidly decreasing, and finally ceasing altogether by the time the throttle valve is wide open.

A further object of the invention is to provide 10 means whereby the carburetor operates as an air-valve carburetor, regulating the fuel by the metering pin at all positions of the throttle except when it is wide open, but for wide open throttle the metering pin and air valve no longer function, the mixture being then controlled 15 entirely by the volume of air flowing through the venturi and the size of the nozzle in the venturi, the same as in a plain-tube carburetor.

A further object of the invention is to provide 20 means whereby the metering pin can be adjusted to regulate fuel flow when the carburetor is operating as an air-valve carburetor, and further to provide means to change the disposition of the fuel nozzle to regulate the fuel flow when the throttle is wide open and the carburetor 25 operating as a plain-tube carburetor.

Means for carrying out the objects of the invention are clearly explained in connection with the accompanying drawings, in which—

Fig. 1 is a side elevation of a carburetor constructed in accordance with the invention.

Fig. 2 is a side elevation looking from the left side of Fig. 1.

Fig. 3 is a central section looking in the same direction as Fig. 1.

Fig. 4 is a view of the air velocity valve, looking downwardly into the carburetor.

Fig. 5 is a central sectional view of the venturi, throttle valve, air valve, and the air velocity valve in the venturi.

Fig. 6 is a vertical sectional view showing the metering pin and nozzle bar, some of the other parts being omitted.

Fig. 7 shows graphs of suction and mixture ratios produced by the invention.

The invention is illustrated as applied to a down draft carburetor, which has an air inlet 5, a mixing chamber 6, and a fuel mixture outlet 7 adapted to be connected with the engine intake manifold. The mixing chamber is formed with a venturi 8 into which fuel is admitted through nozzles 9.

The throttle valve 10 within the outlet 7 is mounted on a stem 11 which is provided with an arm 12 connected to a throttle control rod 55

13. An unbalanced air valve 14 within the air inlet 5 is mounted on a stem 15, on which an arm 16 is secured. A telescopic link connecting the two valve arms 12 and 16 comprises a rod 17 pivotally connected to the arm 16, with a sleeve 18 threaded on the rod 17 and formed internally with a solid portion 18^a normally resting on the upper end of a rod 19 which is pivotally connected to the arm 12 and slidable in 10 the sleeve 18.

The valve 14 is therefore free to close regardless of the position of the valve 10 and may be opened only by air flow or suction. A cam follower 20 is slidably mounted on the rod 19 and normally rests against an extension 21 of the arm 12, which is formed with a cam 24. A light coil spring 22 is disposed between the cam follower 20 and the end of the sleeve 18 and under certain conditions, as hereinafter explained, exerts a light pressure tending to close the valve 14. The sleeve 18 has a threaded adjustment on the rod 17 merely to maintain proper length of the linkage between the valves 14 and 10 and to correct it for wear and manufacturing tolerances. A spring 23 at the upper end of the sleeve retains the latter in its adjusted position.

Fuel is fed from a well 25 through a duct 26 to the nozzle openings 9 in a bar 26^a, which extends transversely of the mixing chamber. A metering pin 27 in the well is connected through a link 28 to one end of a cross arm 29 on the valve stem 11 at the opposite side of the carburetor from the throttle arm 12. Thus the pin 27 is raised as the throttle is opened and the tapered flat surface 30 of the pin allows more fuel to be fed to the nozzle. An accelerator pump 31 is connected by a link 32 to the opposite end of the cross arm 29 and is adapted to draw fuel from the well 25 and, as the throttle is opened, to inject it through a duct 33 and jet 34 into the intake passage.

A choke rod 35 is connected to an arm 36 which is mounted on a pivot 37 secured to the carburetor casing. A tension spring 38 connects a pin 39 on the arm 36 to a pin 40 on a lateral extension 41 of the upper valve arm 16. Normally, the pin 39 is in alignment with the air valve axis 15 so that the spring 38 is radial to the axis and has no effect on the opening or closing of the air valve. However, when the choke rod 35, as shown in Fig. 1, is moved to the right, the arm 36 and pin 39 are moved to the right and the spring 38 exerts a torque on the air valve 14 which tends to hold it closed whenever the throttle is opened.

A screw 42 threaded into a lug on the arm 12 engages an abutment 43 to limit the closure of the throttle valve 10 to idling position. This abutment 43 extends laterally from a bar 44 which is pivotally mounted on the throttle valve axis 11. The upper end of this bar has a slot 45 which is engaged by a pin 46 on the arm 36 so that, as the latter is swung in a direction to cause the air valve 14 to act as a choke, the bar 44 is swung slightly in a direction to raise the abutment 43 and open the throttle slightly. This also allows more fuel to pass the metering pin 27.

In the drawings, the carburetor is shown set for idling the engine on which it is used. Air valve 14, throttle valve 10 and metering pin 27 are not completely closed. There is enough flow past the throttle valve 10 to create a vacuum around the nozzle 9. Arm 29 is rigidly connected to the valve shaft 11 and link 28 connects it to metering pin 27. Cam follower 20 is held down on the cam 24 by the spring 22. This spring is

completely collapsed and the partition 18^a in the sleeve 18 is resting on the end of the rod 19. At this point, the spring has nothing whatever to do with the suction or vacuum in the mixing chamber. Consequently, it has nothing whatever to do with mixture ratios, because it is in effect cancelled out of the system, and the two valves 10 and 14 operate the same as if they were rigidly linked together.

As the throttle valve 10 is progressively opened, the metering pin 27 is also opened, and air valve 14 follows throttle valve 10, keeping spring 22 completely collapsed, and the partition 18^a in sleeve 18 rests solidly on the end of rod 19. It is understood that the vacuum or suction under the unbalanced valve 14 keeps spring 22 completely collapsed so that it has no effect on air valve 14 when the throttle is opened slowly or when it is not being moved at all, provided that the engine is running.

The angles of the valves 14 and 10 and of the arms 29, 21 and 16 are of such a relation to each other that, upon movement of the throttle valve 10 toward an open position, the static suction around the nozzle 9 gradually diminishes, and the increased volume of air flowing past the nozzle 9 through the venturi 8 gradually and progressively changes the static suction around the nozzle to a dynamic suction, as represented graphically by a straight upwardly inclined curve. Naturally, a progressive increase of nozzle suction, a progressive increase of air flow and a progressive increase of fuel gives proper mixture ratios in all throttle positions.

The curves in Fig. 7 show the performance of this carburetor. Curves A and B show the nozzle suction curve and the mixture curve respectively, when the throttle is gradually opened from engine idling to high speed. These curves are produced when the carburetor is operating as an air-valve carburetor and the valves 10 and 14 act as though they were solidly linked together. It will be observed that the suction curve increases progressively, while the mixture ratio remains the same, until the throttle is nearly wide open. At that point, the mixture becomes richer, as indicated by curve B. This is due to the fact that the metering pin 27 no longer controls the fuel flow. The flow is then controlled entirely by the nozzle 9.

In the event that the throttle is not gradually opened, but opened suddenly for a short distance, the mixture becomes momentarily richer, as indicated at line D. This is because the cam 24 on the arm 21 raises the follower 20 and increases the tension of the spring 22, which tends to delay the opening of the air valve 14, but as soon as the engine speed picks up, the vacuum will increase and again collapse the spring 22, which leans out the mixture again back down to the line B.

The curves E and F show nozzle suction and mixture ratios from low to high engine speed when the throttle is kicked wide open and the carburetor is operating as a plain-tube carburetor. The suction on the nozzle is created entirely by air flow and velocity. The metering of fuel is done entirely by the nozzle 9 because the metering pin no longer functions when the throttle valve 10 is wide open. It is to be understood that both valves 10 and 14 go wide open simultaneously and the spring 22 has no effect whatever under these conditions. Fig. 7 is used to show what is necessary in nozzle suction and mixture ratios to obtain the desired performance, and to produce

ich curves, the carburetor must be constructed s I have specified.

It will be observed that under light loads, the arburetor operates as an air-valve carburetor nd on a lean mixture to give the best economy ut under full load, when the throttle is wide pen, it operates as a plain-tube carburetor with ixtures for maximum power. This combination eliminates the use of step-up jets, power jets r compensating wells, and makes the carburetor ery simple to manufacture.

I am aware that other inventors have constructed carburetors having two valves and a nozzle between them, and also having spring devices, ut none of these will produce the essential suction and mixture ratio curves that my carburetor oes. My construction is not a mere mechanical improvement upon carburetors heretofore proposed, but involves a new principle in the control f the air valve.

In order to automatically enrich the mixture or acceleration and to prevent stalling of the engine on which my carburetor is used, I have rovided the spring 22, the cam follower 20 and he cam 24. The spring 22 is located around the od 19, one end resting on sleeve 18 and the other n the follower 20, the latter being loose on the od 19. Cam 24 is integral with the arm 21.

When the engine is idling, the spring 22 is completely collapsed or compressed and the partition 8^a in the sleeve 18 rests solidly on the end of the od 19. In the event that the engine has a tendency to stall, due to being cold, the vacuum in he mixing chamber will naturally decrease and he suction against the air valve 14 will also de-rease. With this low vacuum in the mixing hamber, the spring 22 will no longer be colapsed. It will expand against the sleeve 18 and end to close the air valve 14, which in turn will ncrease the suction around the nozzle 9 and en-ich the mixture to prevent stalling. As the en-ine warms up, the vacuum will increase, which will again collapse the spring 22, and there will hen be no lost motion in the link that connects he two throttle valves together. In other words, he two valves will act as though they were linked lidily together.

In carburetors having an air valve of this type, he air stream varies in its course in relation to he fuel nozzle as the air valve is moved either oward an open or closed position. This causes variation in suction on the nozzle, which in turn varies the mixture ratios and affects distribution. I have provided means whereby the air always passes the nozzle in the same direction, regard-ess of air valve position. See Figs. 4 and 5. I use two wafers 47 hinged around the nozzle 26^a, which may be termed an air velocity valve. When he valves 10 and 14 are closed, these wafers are closed against the venturi by a small spring 48, und even though the air is deflected against the arburetor wall, it is again straightened up and flows vertically past the jets. As the valves 10 and 14 are opened further, air velocity forces these wafers wide open and they hang in a verti-ral position, but at these times, the air valve 14 s open and does not deflect the air away from he nozzles.

The conventional metering pins used in carburetors, especially those using a tapered pin operating in an orifice, are entirely too sensitive, due o the fact that a very little movement greatly varies the fuel flow and also the least bit of wear n the operating mechanism will cause a great variation in the mixture ratios. I have overcome

this difficulty by using a piston-type metering pin 27, as shown particularly in Fig. 6. This pin has a flat tapered side 30, and with this construction, a long movement can be used to meter fuel, which eliminates sensitivity that is common with the conventional metering pin of this type. To absolutely control all of the metering by the flat taper 30, the suction in the mixing chamber holds the pin snugly against the cylinder wall, and even though considerable tolerance 10 is used in manufacturing, or wear takes place, no fuel can pass except as permitted by the tapered flat side.

I have also provided means for adjusting the mixture ratios or fuel flow when the carburetor is operating as an air-valve carburetor. A piston 49 within the upper end of the pin 27 is formed with a hole 50, which receives the upper end of the link 28. The piston 49 is not threaded, but might be termed floating, since it is held down against a spring 51 by a screw 52, which is threaded into the pin 27. If the screw is turned down, the metering pin is raised to enrich the mixture. If the screw is backed out, the pin is lowered to 20 lean out the mixture.

To adjust the mixture ratios when the carburetor is operated as a plain-tube carburetor, the nozzle bar 26^a can be rotated by loosening a screw 54 and shifting the arm 53, which is rigidly connected to the nozzle bar. This changes the 30 angle of the nozzle openings 9, which are in the bar 26^a. When the openings are at right angles to the air flow, the maximum amount of fuel will be drawn out, but as they are moved toward a position parallel to the air flow, one of them will 35 function as an air bleed and thereby lean out the mixture. This adjustment is very convenient, be-cause the owner can adjust his own carburetor for altitude or climatic conditions.

In the normal operation of the carburetor, it 40 will be noted that the choke spring 38 is exactly radial to the axis of the air valve so that it has no effect. When the choke rod is pulled out, however, the arm 36 is swung about its pivot, moving the lower end of the choke spring to the right, 45 as shown in Fig. 1, so that it resists the opening of the air valve and chokes the air flow into the mixing chamber.

It is to be understood that the specific construction herein shown and described is merely 50 illustrative, that the invention can be used for different types of carburetors, whether down-draft, updraft, single or duplex carburetors, and that it also includes such modifications as may be embraced within the scope of the appended 55 claims.

I claim:

1. A carburetor comprising a fuel mixture chamber having an outlet adapted to be connected to an engine intake manifold, a venturi 60 in the chamber, a fuel jet opening into the venturi, an air inlet to the chamber, a throttle valve for said outlet, an unbalanced air valve for the air inlet adapted to be opened only by air flow and suction, each valve having an arm 65 secured thereto for controlling its position, an extensible link connecting said arms, a spring exerting pressure tending to extend the link when the valves are nearly closed, the opening of the two valves being substantially the same when the link is of minimum length, the air valve being open less than the throttle valve when the link is extended, and means actuated by the throttle valve arm to increase the pressure of said spring 70 when the extensible link is of minimum length 75

such as occurs when the two valves start to open simultaneously and at the same rate whereby the opening of the air valve is delayed and then to decrease said pressure as they open wider.

- 5 2. A carburetor comprising a fuel mixture chamber having an outlet adapted to be connected to an engine intake manifold, a venturi in the chamber, a fuel jet opening into the venturi, an air inlet to the chamber, a butterfly 10 throttle valve for said outlet, an unbalanced butterfly valve for the air inlet adapted to be opened only by air flow and suction, arms secured to the respective valve axes, a link comprising telescopic sections connected to the respective arms, 15 the opening of the two valves being substantially the same when the link is of minimum length, the air valve being open less than the throttle valve whenever the link is extended, an abutment member slidable on one of the sections, a spring 20 adapted to exert pressure between said abutment member and the other section tending to extend the link, and a cam on the throttle arm operable during the initial opening of the throttle when the extensible link is of minimum length such 25 as occurs when the air valve and throttle valve open simultaneously at the same rate to move the abutment member in a direction to compress the spring whereby opening of the air valve is delayed and upon a wider opening of the throttle 30 in a direction to progressively release the spring.
3. A carburetor comprising a fuel mixture chamber having an outlet adapted to be connected to an engine intake manifold, a venturi in the chamber, a fuel jet opening into the 35 venturi, an air inlet to the chamber, a butterfly throttle valve for said outlet, an unbalanced butterfly air valve for the air inlet adapted to be opened only by air flow and suction, an arm secured to the air valve axis and extending radially 40 therefrom, a tension spring connected at its outer end to said arm, and a choke actuating member to which the inner end of said spring is connected at a point normally in line with the air valve axis so that the spring has no effect upon the 45 opening or closing of the air valve, said choke actuating member being shiftable to move the inner end of said spring away from the valve axis in a direction to cause the spring to exert a torque on the air valve tending to hold it closed, whereby 50 the air valve functions as a choke.
4. A carburetor comprising a fuel mixture chamber having an outlet adapted to be connected to an engine intake manifold, a venturi in the chamber, a fuel jet opening into the 55 venturi, an air inlet to the chamber, a butterfly throttle valve for said outlet, an unbalanced butterfly air valve for the air inlet adapted to be opened only by air flow and suction, each valve having an arm secured thereto for controlling its 60 position, an extensible link connecting said arms, a light spring exerting pressure tending to extend said link and thereby retard the opening of the air valve when the throttle valve is partly opened from idling position, an independently pivoted 65 choke actuating member, a tension choke spring with its inner end anchored to a point on said member normally in line with the air valve axis and its outer end anchored to the air valve arm at a distance from the valve axis so that it has no 70 effect upon the opening or closing of said valve, and means for shifting the choke actuating member and thereby moving the inner end of the

choke spring in a direction to cause the latter to exert a torque on the air valve tending to hold it closed, whereby the air valve functions as a choke.

5. A carburetor comprising a fuel mixture chamber having an outlet adapted to be connected to an engine intake manifold, a venturi in the chamber, a fuel jet opening into the venturi, an air inlet to the chamber, a butterfly throttle valve for said outlet, an unbalanced butterfly air valve for the air inlet adapted to be opened only by air flow and suction, each valve having an arm secured thereto for controlling its position, an extensible link connecting said arms, a light spring exerting pressure tending to extend said link and thereby retard the opening of the air valve whenever the throttle valve is partly opened from idling position, means to increase the pressure of said light spring as the two valves start to open simultaneously and then to decrease said pressure as they open wider, an independently pivoted choke actuating member, a tension choke spring with its inner end anchored to a point on said member normally in line with the air valve axis and its outer end anchored to the air valve arm at a distance from the valve axis so that it has no effect upon the opening or closing of said valve, and means for shifting the choke actuating member and thereby moving the inner end of the choke spring in a direction to cause the latter to exert a torque on the air valve tending to hold it closed, whereby the air valve functions as a choke.

6. In a carburetor, a fuel mixture chamber with an air inlet, a fuel inlet, and an outlet adapted to be connected to an intake manifold, a main throttle valve swingable to control said outlet, an arm connected to and arranged to swing about the same axis as the throttle valve, an unbalanced auxiliary valve controlling the air inlet and adapted to be opened only by air flow and suction, an extensible push connection consisting of two relatively movable members, the first of which is pivotally connected to the throttle valve arm and the second of which is pivotally connected to the auxiliary valve, cooperating stop means carried by said extensible members for limiting the opening of the unbalanced valve to the same degree as the throttle valve, resilient means carried by the extensible push connection which exerts a force tending to extend the extensible connection and retard the opening of the unbalanced valve as the throttle valve is opened, a follower movably mounted on the first of said members and positioned between the resilient means and the arm for operating said throttle valve, a cam having an uphill and down-hill portion carried by the throttle valve arm, said uphill portion arranged to engage the follower during the initial opening of the throttle to move the follower away from the point at which the first member is connected to the throttle valve arm whereby the resilient means is stressed to retard the opening of the auxiliary valve and upon a wider opening of the throttle said down-hill portion of the cam engaging the follower whereby the spring is progressively relieved of said stress and the follower moves in a direction toward the point at which the first member is pivoted to the throttle valve arm.
